(57) CLAIM

The ornamental design for a feminine hygiene emergency holder, as shown and described.

DESCRIPTION

FIG. 1 is a perspective view of a feminine hygiene emergency holder, showing my new design in a closed configuration;

FIG. 2 is a top plan view of FIG. 1 thereof;

FIG. 3 is a bottom plan view of FIG. 1 thereof;

FIG. 4 is a front elevation view of FIG. 1 thereof;

FIG. 5 is a rear elevation view of FIG. 1 thereof;

FIG. 6 is a left side elevation view of FIG. 1 thereof;

FIG. 7 is a right side elevation view of FIG. 1 thereof;

FIG. 8 is another perspective view of FIG. 1 thereof, showing the feminine hygiene emergency holder in an open configuration and in use holding feminine hygiene products;

FIG. 9 is another perspective view of FIG. 8 thereof, showing the feminine hygiene emergency holder empty;

FIG. 10 is a top plan view of FIG. 9 thereof;

FIG. 11 is a bottom plan view of FIG. 9 thereof;

FIG. 12 is a front elevation view of FIG. 9 thereof;

FIG. 13 is a rear elevation view of FIG. 9 thereof;

FIG. 14 is a left side elevation view of FIG. 9 thereof; and,

FIG. 15 is a right side elevation view of FIG. 9 thereof.

The broken lines depict environment that forms no part of the claimed design.

1 Claim, 14 Drawing Sheets
